VALVE HEAD FOR AIR ENGINES

Filed Oct. 13, 1926

BY

ATTORNEY

UNITED STATES PATENT OFFICE

NATHANIEL KOEHN, OF OAKLAND, CALIFORNIA

VALVE HEAD FOR AIR ENGINES

Application filed October 13, 1926. Serial No. 141,338.

The present invention relates to a valve head for air engines and is, in part, divisional to my co-pending application, Serial No. 50,661, filed August 17, 1925. In the latter application, I described an oscillating air engine and a valve head in connection therewith, the latter being designed to feed a limited amount of a pressure medium to the engine, while the latter was idling and to automatically increase the pressure medium delivered to the engine upon the attaching of a load thereto. The present invention describes a valve head having substantially the characteristic of that described in the said co-pending application, but having a few structural improvements incorporated therein.

The principal object of the present invention is to provide a valve head that, upon manual operation of a valve, will deliver a limited amount of a pressure medium and that will automatically increase the amount delivered when back pressure is exercised due to the assumption of a load by the engine to which the valve head is attached.

Further objects and advantages of my invention will appear as the specification proceeds.

The preferred form of my invention is illustrated in the accompanying drawing in which—

Figure 1 shows a vertical section thru a complete oscillating air engine, having my valve head attached thereto,

Figure 2 is a horizontal section thru the engine as viewed from line 2—2 of Figure 1, and

Figure 3 a top plan view of the entire device.

While I have shown only the preferred form of the invention, it should be understood that various changes or modifications may be made within the scope of the claims hereto attached without departing from the spirit of the invention.

The engine 1 may be described as being of the oscillating type and as consisting of a cylinder 2, a shaft 3 arranged centrally therein, a piston 4 fixed to the shaft made in the shape of a yoke and formed with two piston heads 6 adapted to oscillate in an annular chamber

7 within the cylinder 2, and a valve mechanism shown at 8 which is more particularly described in the co-pending application and which is constructed to admit air for a pressure medium into the annular chamber on one side, while exhausting the pressure medium on the opposite side for swinging the piston in one direction, and to be reversed by the piston itself at the end of its stroke for producing a reverse condition in which the piston is actuated in an opposite direction.

The present invention is principally concerned with the valve head 9 which admits a pressure medium to the valve 8. My valve head comprises a cap 11 formed with a flange 12 adapted to be threaded into the cylinder 1. The body portion of the cap is recessed as shown at 13, the recess being formed in two steps to provide a shoulder 14. A sleeve 16 formed with a head 17 thereon has a diaphragm 18 fitting therearound, said diaphragm having its periphery clamped against the shoulder 14 by means of a fitting ring 19. A leaf spring 21 bent as shown in Figure 1 is slipped over the sleeve 16, the sleeve 16 extending thru the central portion of the same, and a suitable facing element 22 serves to clamp the central portion of the diaphragm against the head 17. One end of the leaf spring rests against the inner face of the cap as shown at 23, while its other end rests on a screw 24 threaded into the head. A reduced extension 26 passes thru a registering hole in the spring 21. It will be noted that by operation of the screw 24, the tension on the spring 21 may be increased or decreased. After inter-position of another facing member 27, a diaphragm 28 is slipped over the sleeve 16 and is held in place by means of a nut 29 threaded onto the sleeve 16. The rim of the diaphragm bears against the bottom face of the flange 12. A plug 31 is threaded into the sleeve 16 to form an abutment therein, the side of the plug being shaved as shown at 32 to allow a pressure medium to pass the plug.

The cap terminates at its upper end in a tubular element 33 which communicates with the recess 13 thru a comparatively small opening 34, the tube being sufficiently wide to

form a shoulder 36 around the aperture 34. A plug 37 is threaded downwardly into the tube 33 to rest on the shoulder 36 and is formed with a valve seat 38. A second plug 39 is threaded into the sleeve 33 merely to serve as a guide element for the valve 41 which passes thru the latter and is threaded into the plug 37 until it comes to rest on the valve seat 38. The valve 41 consists of a hollow stem with a conical bottom fitting the valve seat 38 and provided with transverse ports 42 adapted to discharge a pressure medium from the inside of the valve 41 into a space 43 formed in the outer face of the valve 41 by flattening certain portions of the lower end thereof. It will be noted that from this space 43, the pressure medium may escape into the recess 13 and the sleeve 16 when the valve 41 is lifted off its seat 38.

The valve 41 is formed at the lower end thereof and on the inside with a valve seat 44 adapted to accommodate the valve 46 provided at the end of a plunger 47 which latter has sufficient play in the hollow space of the valve 41 to allow a pressure medium to pass the same and which is normally forced downwardly so as to bring the valve 46 into contact with its seat by a spring 47 bearing at its upper end against a hollow plug 48 threaded into the valve 41. The valve 46 has a pin 51 extending downwardly therefrom which latter is adapted to be operated by the plug 31 in the sleeve 16 when the latter is raised due to the fact that a pressure medium bears on the bottom face of the diaphragm 28.

Any suitable hose connection 52 may be secured to the valve 41 in the manner shown in Figure 1. A winged element 53 may be fastened to the valve 41 by means of a set screw 54 so that its wings 56 encircle the tubular element 33 and may be secured in any position desired by means of a set screw 57 passing thru one of the wings into contact with the outer face of the tubular element 33 which latter may be knurled for this purpose.

The operation of my valve is as follows: To start the engine, the valve 41 is turned slightly by means of the winged element 53 so as to lift the valve off its seat. The pressure medium may now enter thru the hose 52 into the hollow of the valve 41 and thru the ports 42 into the spaces 43, past the valve seat into the aperture 34 and the recess 13 and finally into the sleeve 16 which discharges the same into the engine for operating the latter. It will be noted that during this operation, the valve 46 remains seated and no part of the pressure medium passes thru the latter valve. The pressure supply is very limited and causes the engine to idle at a desired speed, the latter being regulated by the extent to which the valve 41 is lifted off its seat.

When a load is attached to the engine, as,

for instance, when the shaft 3 is connected to valve to be ground, the pressure within the engine is increased due to the resistance offered by the work and pressure is brought to bear on the bottom face of the diaphragm 28 which latter is raised thereby. The raising of the diaphragm causes the plug 31 in the sleeve 16 to raise the valve 46 off its seat and the pressure medium can now enter the engine directly thru the bottom of the valve 41 at an increased rate. It will thus be seen that the higher the resistance offered by the work to be done, the more compressed air will enter the engine for driving the same at an increased speed.

It will be noted that the action of the diaphragm can be controlled to some extent by adjustment of the spring 21 by means of the screw 24. As the tension of the spring 21 is increased, it takes more pressure to render the diaphragm active as a valve operating medium and less compressed air will be delivered to the engine at a given load. If it is desired to increase the charge, the tension of the spring 21 should be lessened. Suitable directions for adjusting the tension may be given by the markings on cap 11 as shown in Figure 3.

I claim:

1. A valve for a pressure medium comprising a recessed element having a diaphragm stretched across the recess, a cored member supported in the diaphragm, means for admitting a pressure medium through the said element to the cored member providing a double path for the pressure medium, a manual control for one of the paths and a diaphragm operated control for the second path.

2. A valve for a pressure medium comprising a recessed element having a diaphragm stretched across the recess, a cored member supported in the diaphragm and a valve arranged for admitting a pressure medium through the element to the cored member having means associated therewith tending to close the same and being subject to the action of the cored member for opening the same when back pressure is exercised on the diaphragm, and means independent of the valve for admitting the pressure medium thru the element to the cored member.

3. A valve for a pressure medium comprising a recessed element having a diaphragm stretched across the recess, a cored member supported in the diaphragm, a valve arranged for admitting a pressure medium through the element to the cored member having means associated therewith tending to close the same and being subject to the action of the cored member for opening the same when back pressure is exercised on the diaphragm and a by-pass for the pressure medium allowing the diaphragm to become active.

4. In a device of the character described,

a flanged cap having a diaphragm stretched across the flange thereof, spring means tending to force the diaphragm outwardly, a sleeve supported in the diaphragm and means for admitting a pressure means through the cap to the sleeve comprising a main passage and a by-pass, a manually operated control valve for the by-pass, a control valve for the main passage and an operative connection between the latter valve and the sleeve allowing the latter to operate the former.

5. In a device of the character described, an element having a hollow valve seated therein, and a second valve seated in the hollow of the first valve, manual means for controlling said first valve to permit a pressure medium to be guided from the inside thereof to its seat, and means operated by a diaphragm for controlling the movement of said 10 second mentioned valve.

6. In a device of the character described, a recessed element having a diaphragm stretched across the recess thereof, spring means tending to force the diaphragm outwardly, a sleeve supported in the diaphragm, manually controlled means for admitting pressure thru said element to said sleeve, and a control valve operated by the movement of said diaphragm when back pressure is applied thereto for admitting a pressure thru 25 the element to the sleeve, as and for the purpose specified.

7. In a device of the character described, an element having a valve seat thereon, a hollow valve adapted to rest on said valve seat, and a second valve mounted in said first mentioned valve, said first mentioned valve having a valve seat therein adapted to receive said second mentioned valve, manual means for controlling the movement of said first mentioned valve, and means controlled by back pressure 30 on a diaphragm for operating said second mentioned valve.

In testimony whereof I affix my signature.
45 NATHANIEL KOEHN.
